UNITED STATES PATENT OFFICE.

RAYMOND L. FOSTER, OF APPONAUG, RHODE ISLAND.

LIQUID-FUEL BURNER.

Application filed April 14, 1924. Serial No. 706,330.

This invention relates to improvements in liquid-fuel burners and particularly to burners of the gravity-feed type.

A principal object of the improvement is 5 to provide a simple, compact burner structure which may be applied to use with furnaces or boilers of conventional type without alteration therein, and one which will operate more efficiently to obtain complete 10 combustion of the fuel without carbonization.

Another object of the improvement is to provide a liquid-fuel burner which may be constructed as a single unitary device without 15 extra parts or attachments, and which may be extended in series to increase its capacity.

Another object of the improvement is to provide a burner which may be constructed 20 in series with a plurality of units combined in a single structure.

Another object of the improvement is to provide a burner in which there are no pipes exposed to the flame or liable to be burned 25 out by the heat generated in the fire-bowl.

Another object of the improvement is to regulate the flow of the fuel to the burner under gravity to maintain a constant uniform feed irrespective of the pressure in 30 the supply-tanks, whereby to prevent flooding or overflow.

Another object of the improvement is to provide self-contained means for pre-heating the fuel in the burner before it is fed to 35 the flame.

Another object of the improvement is to provide a burner having a self-contained steam-generating chamber wherein water may be vaporized and the vapor supplied 40 to the flame to increase the effect of combustion and prevent the deposit of carbon on the burner or on the boiler with which it is used.

Another object of the improvement is to 45 provide for supplying a maximum amount of oxygen to the burner without danger of extinguishing the flame from too strong a draft under extreme conditions in the flue.

Further objects of the improvement are 50 set forth in the following specification which describes a preferred embodiment of the invention as illustrated in the accompanying drawings. In the drawings:

Fig. 1 is a vertical sectional view of the 55 improved burner showing it applied to use in a furnace of conventional type and illus-

trating the regulating-means for the feed of the fuel and the supply of water;

Fig. 2 is an enlarged plan view of the fire-bowl of the burner showing a portion of the air-manifold employed therewith, and also illustrating the arrangement of the damper or valve in the air-duct;

Fig. 3 is an enlarged sectional view of the complete burner taken in the vertical plane 65 of its axis on the line 3—3 of Fig. 2, looking in the direction indicated by arrows α ;

Fig. 4 is a plan view showing a plurality of burner-units embodied in a single structure;

Fig. 5 is a vertical sectional view of the same taken on the line 5—5 of Fig. 4.

Referring first to Figs. 1, 2 and 3, as herein shown the improved burner structure comprises essentially a concaved fire-bowl 2, preferably of substantially hemispherical form, in which is a central burner-nozzle 11 surmounted by an air-manifold 3. The main casting of the burner is constructed with an outer cylindrical wall 4 having a depending bottom flange 5 adapted to rest on the grate G of the furnace F, as illustrated in Fig. 1, or to be supported by any other suitable means. Arranged at diametrically opposite points on the outer wall 4 of the bowl 2 are one or more vertical flues or air-ducts formed by substantially rectangular-shaped tubular extensions 6 constructed as a part of the main casting. The flues 6 extend downwardly a slight distance beyond the bottom of the bowl 2 in order that they may project below the grate or other support on which the burner is held to open into the ash-pit of the furnace. A section of the grate may be removed to allow the flues to enter therethrough into the ash-pit P to provide for an unobstructed passage of the air drawn in through the ash-pit by the draft in the chimney or main flue.

The draft-manifold 3 is preferably constructed as a separate casting and takes the form of a tubular bridge-piece extending across the top of the bowl 2 between the flues 6. As shown in Fig. 3, the down-turned open ends of the draft-tube or manifold 3 are 100 adapted to fit over projecting flanges 9 rising from the top of the air-flues 6. At the center of the manifold 3 the pipe is directed downwardly and formed with an enlarged circular orifice 7 which opens into the center 105 of the bowl 2 above the burner-nozzle 11. In one or both of the air-ducts 6 I pref-

erably employ a check-damper 8, shown at the right in Figs. 2 and 3, to regulate the draft through the manifold 3. The check-valve 8 may be of conventional type such as usually applied to the flue pipes of furnaces, and may have a crank-arm 53 connected by a rod 54 to any suitable hand-control; or the damper may be operated automatically from a thermostat as commonly employed for furnace drafts. By regulating the position of a check-valve 8 the draft through the manifold 3 may be made greater or less in accordance with requirements with different installations to supply the proper amount of oxygen to insure complete combustion of the fuel without loss of heat-units from too free a draft. That is to say, in some cases where the draft through the chimney-flue is too great the draft through the manifold may be checked by closing the damper 8, and if required another damper may be employed in the other air-duct 6 leading into the manifold.

It will be noted from Fig. 3 of the drawings that the fire-bowl 2 has a relatively shallow concavity formed by its hemispherical wall 10, at the center of which rises the stepped nozzle 11 forming the burner proper. In the nozzle or burner 11 is a central orifice 12 having an upper flaring mouth and also an inner downwardly-flaring conical throat 13. Beneath the throat 13 of the burner is the fuel-pre-heating chamber or reservoir 14 formed by a cylindrical wall 15 connecting the concaved wall 10 of the bowl with the lower horizontal wall or base 16. The upright cylindrical wall 15 is spaced inwardly from the outer boundary wall 4 to provide an annular or ring-shaped steam-generating chamber 17 to which the water is supplied for vaporization, and from which the steam issues to be carried to the flame. It is to be noted that the steam-chamber 17 is made as an integral part of the main casting of the burner and is separated from the fire-bowl thereof by a relatively thin wall so that the heat from the burner will be applied to the water in the steam-chamber with a maximum efficiency to generate the vapor as required. The vapor may be passed from the steam-chamber 17 directly into the air-ducts or flues 6 by means of suitable openings 18 cut through the outer wall of the steam-chamber at the top as shown in Fig. 3. In some cases, however, I prefer to use a pipe 24 leading from the steam chamber 17 down into the ash-pit beneath the burner, see Fig. 1, and adapted to supply the steam or vapor to cause it to be passed up through the flues 6 by the draft therein. Either or both of these arrangements may be used as best adapted for the purpose in accordance with the method of operation of the apparatus as later more fully explained.

It will be noted that the fuel-reservoir or

pre-heating chamber 14 is located beneath the center of the bowl of the burner and separated from the area in which the flame is confined by a relatively thin top wall. This provides that the heat from the flame will raise the temperature of the fuel to a point where it becomes gaseous or volatilized. Through this provision the fuel is vaporized in the pre-heating chamber 14, the vapor rising therefrom through the funnel-shaped throat 13 and being emitted at the mouth of the nozzle 11 to be ignited at this point. The fuel-chamber or reservoir 14 is supplied with fuel from suitable tanks, not herein shown, which are elevated above the burner to provide for a gravity-feed thereto. Referring to Fig. 1, the fuel feeds from the tanks through a pipe 19 which usually has a strainer 20 of suitable type applied thereto. The pipe 19 is connected with a vertical pipe 21 which, in turn, leads through a horizontal pipe 22 entering the door in the ash-pit P of the furnace and connected by a length of vertical pipe 23 to the fuel-chamber or reservoir 14. It will be noted by reference to Fig. 1 that the supply-pipe 23 leads into the fuel-reservoir 14 near the outer circumference thereof, the purpose of this arrangement being to cause a current to be set up within the reservoir to keep the fuel swirling therearound. This arrangement has the effect of increasing the tendency of the fuel to be broken up and volatilized to cause it to be exhaled through the burner-nozzle 11 in a vapor.

A control-valve 25 is placed in the feed-pipe 21 near its upper end to regulate the flow of the fuel from the tanks to maintain a more uniform pressure and more constant feed at the burner. At one side of the valve 25 a vent-pipe 33 leads upwardly to be carried to the atmosphere through suitable connections to meet safety requirements as prescribed by the Underwriters' Laboratories. Beneath the control-valve 25 is a suitable shut-off valve 34, and below this is a usual form of feed-regulating valve 35 which may be connected by a chain or cord 36 to be operated automatically from a thermostat. The arrangement of the thermostat-valve 36 being well known and generally employed in the present art it is not herein illustrated or described in detail.

At one side of the furnace F is located a water-tank 40 which supplies water to the steam-chamber 17 of the burner. The tank 40 is supplied from the service pipe line through a feed-pipe 41 having a shut-off cock 42, see Fig. 1. The water tank 40 contains the usual ball-cock by means of which the level of the water is regulated in a well-known manner. The ball-cock is adjusted to maintain the level of the water in the tank 40 at such a height that the water in the steam-chamber 17 will very little more

than cover its bottom, see Fig. 1. The water feeds from the water tank 40 through a pipe 45 entering through the ash-pit door of the furnace and leading up through the bottom 5 of the burner-casting 2 into the steam-chamber 17.

Referring to Fig. 1, the usual overflow drain is applied to the bowl of the burner to prevent flooding with oil, and may consist of 10 a vertical pipe 48 leading from the bowl at one side of the nozzle 11 and connected to drip into a bucket 49 suspended on the operating-lever of a shut-off valve 51. Should the fuel be fed to the burner after the flame 15 is extinguished, the oil rising in the bowl will drain out through the pipe 48 into the bucket 49 and weight the latter to cause it to drop through gravity to close the shut-off valve 51, this being a usual arrangement 20 in accordance with safety requirements to eliminate fire hazard.

Surmounting the top of the burner nozzle 11 is an improved flame-spreader or deflector 57 which also acts as a draft-baffle or protector to prevent abnormal blasts of air from extinguishing the flame. As shown in Figs. 2 and 3 my improved flame-spreader and draft-baffle 57 may consist in a hub or support 58 adapted to rest within the tapered 25 mouth of the nozzle 11 and having a pipe-nipple 59 projecting downwardly through the contracted portion of the mouth to hold it in position. The pipe or nipple 59 is preferably filed off or flattened on its sides to provide slight spaces or openings to allow 30 excess oil to drain back into the reservoir 14. Projecting upwardly from the hub 58 of the flame-spreader 57 are two diverging arms 60, at the top of which is supported a flat circular cap or disk 61. It will be noted 35 from Fig. 3 that the cap 61 of the spreader 57 is set at a height to bring it within the central orifice or air-opening 7 of the manifold 3. The current of air passing downwardly from the opening or orifice 7 is thus caused to be parted at the center and diverted outwardly at either side of the fuel-nozzle 11. This prevents the draft from 40 blowing directly against the flame and thus guards against the danger of a sudden blast 45 of air extinguishing the flame and putting the burner out of operation. Furthermore, the spreader 57 acts on the flame rising from the nozzle 11 of the burner to deflect it outwardly and downwardly as indicated by the 50 arrows in Fig. 3. In this way the flame is caused to mushroom and to be spread outwardly and downwardly to cause it to hover in the bowl of the burner. The effect of 55 this is to provide a substantially fountain-like sheet of flame spreading from all sides of the burner and hovering within the bowl, from which it is deflected to be thrown outwardly and upwardly with an intense heat. 60 The flame rising from the burner heats the

manifold 3 and thus raises the temperature of the air passing therethrough so that it will have greater efficiency in atomizing the fuel vapor to supply a large amount of oxygen to raise the effect of combustion to 65 produce the maximum degree of heat.

Figs. 1, 2 and 3 of the drawings illustrate my improved burner embodied in a single unit, the type here shown being adapted for general household use with average-sized 70 furnaces and boilers. Where greater capacity is required, however, as for instance in large residences or for office and institutional buildings, the units may be multiplied in a single structure by extending them 75 in series. That is to say, one, two, three or more of the burners may be constructed in a unitary casting as indicated in Figs. 4 and 5. It has been demonstrated that a plurality of burners arranged in series as 80 described will increase the efficiency of the apparatus while also conserving the fuel and making for greater economy in both small- and large-capacity installations. As shown 85 in Figs. 4 and 5, the bowls 2 of the burner are joined at their circumference with individual steam-chambers extending around the rims of the bowls and separated by a vertical wall or partition 62. The arrangement of the burners in this modification is 90 substantially the same in other respects as first described, each bowl having its own manifold 3 surmounting the air-ducts 6 and also provided with its individual burner-nozzle 11 rising above the fuel-chamber 14.

In Figs. 4 and 5 I have illustrated a somewhat different form of flame-spreader and draft-baffle 63. The device functions in substantially the same manner as before explained, but is of slightly different construction having a ring-portion 64 adapted to seat in the uppermost groove surrounding the stepped nozzle 11. Rising from the ring 64 are two legs or arms 65 which support the circular cap 66. This form of device is set in place with its ring surrounding the tip of the nozzle and is held in the groove by gravity so that it may be readily lifted off when it is required to clean the burner.

Having now described the construction and arrangement of my improved burner in detail, its method of operation will next be explained. The burner is applied to position in the furnace by resting it on the grate G or supporting it from any suitable foundation, and usually a bed of cinders or broken refractory material is spread across the top of the grate to completely fill the space around the burner and prevent draft therethrough. For a most effective air-seal the space around the burner may be filled with wet asbestos and covered with fine sand to the top of the bowl 2, see Fig. 1. The manifold 3 is applied to the top of the burner casting 2 by merely setting it over

the flanges 9 on the vertical air-ducts 6 and the flame-spreader 57 is set in place over the mouth of the burner-nozzle 11. The burner is then piped in accordance with any suitable arrangement, such as shown in Fig. 1 and previously described, with the feed leading from the tanks through the control-valve 25. A suitable water-tank is placed at the side of the furnace and connected to the steam-chamber 17 of the burner casting in the manner as previously explained. The installation of the burner requires no cutting away of the furnace or boiler or other fitting or alteration.

With the burner installed as above explained the valve 34 is opened and the fuel will feed down through the pipe 21, thence through the pipe 22 and up through pipe 23 into the reservoir 14. The vapor rising from the fuel is ignited at the mouth of the nozzle 11 and the draft entering through the air-ducts 6 will be drawn up through the manifold 3 and expelled downwardly around the nozzle to supply the oxygen to the flame. As the fuel in the reservoir 14 becomes heated from the effect of combustion around the nozzle 11 it is volatilized and hence the vapor rising therefrom will issue in increasing volume until combustion is at the maximum, whereupon the feed of the fuel is regulated by means of the shut-off valve 34 or the automatic thermostat-valve 36 to control the flame in accordance with the degree of heat required. The combustion in the bowl of the burner heats its wall 10 to raise the temperature of the water in the steam-chamber 17 and the steam or vapor rising therefrom issues through the passages 18 into the air-ducts 6 to commingle with the air drawn through the manifold 3 and supplied to the flame around the nozzle 11. In most cases I prefer to provide the pipe 24 leading from the steam-chamber 17 down into the ash-pit or, if required, several of these pipes may be employed and the orifices between the chamber and the air-ducts 6 may be eliminated, as indicated in Fig. 1. In such case the effect will be the same, that is to say, the air in the ash-pit will be humidified before it passes into the air-ducts 6 and is supplied to flame at the burner nozzle 11. The humidified air passing through the manifold 3 and supplied to the flame increases combustion to the maximum and the moisture content in the air effectually prevents carbonization of the fuel and thus eliminates any sooty deposit on the parts of the burner or on the boiler sections within the furnace. It is well known that when oil is "cracked" or vaporized under the effect of heat a residue is left in the form of carbon. With the present improved apparatus the introduction of the moisture-saturated air causes this carbon to be consumed by chemical action and therefore no deposit

collects around the burner orifice or at other points. It has been demonstrated that the present improved type of burner may be operated for long periods without showing the slightest sign of soot or carbon, this result being accomplished through the thorough oxidization of the fuel vapor by the application of the steam-saturated air as above explained. It is further to be noted that the arrangement of the steam-chamber 75 17 surrounding the oil-reservoir 14 provides that the water will absorb the excess heat from the sides of the oil-chamber so that carbon will not form on its walls. The pipe 24 serves as a vent not only for the steam from the generating-chamber 17, but also to carry the heat units down into the ash-pit P so that in this way the walls of the burner never become excessively hot.

As a further improvement, the flame-spreader acts to mushroom and expand the flame to the outer walls of the fire-pot, besides serving to distribute the draft to obtain the maximum effect therefrom. In addition, the cap or baffle at the top of the spreader prevents the extinguishing of the flame under a sudden blast, as for instance during severe storms or disturbances in the weather, my improved device being practically proof against accidental quenching or extinguishing of the flame under any conditions.

It will be observed that my improved burner is exceedingly simple in structure while being of compact form without auxiliary attachments or extensions applied to the burner casting. It is also to be noted that there are no pipes projecting from the burner and exposed to the flame and thus liable to be burned through. The main casting of the burner is of ingenious design to comprehend within its walls the several compartments required, namely, the main bowl, the fuel-reservoir arranged underneath, the surrounding steam-chamber, and the air-ducts which lead into the overhead manifold. All of these several parts of the burner being combined in one piece make for a neater and more finished mechanical structure, besides cheapening the cost of production and also increasing its efficiency for the reasons before given. In fact, my improved burner in each and every feature of design and construction embodies an improved method of functioning for maximum efficiency and particularly for the prevention of carbonization and the loss of heat units through lack of complete combustion.

While I have herein described and illustrated a preferred type of construction of the burner with certain modifications shown in connection therewith, it is to be understood that other changes may be made in the form and arrangement of the parts of the device without departing from the spirit

or scope of the invention. Therefore, without limiting myself in this respect, I claim:

1. A liquid-fuel burner comprising in a unitary structure, a fire-bowl having a burner-orifice therein, means for pre-heating the fuel comprising a reservoir extending laterally beneath the bottom wall of the bowl in communication with the burner-orifice, and a steam-generating chamber also arranged beneath the bowl and having means for supplying steam to the flame in the bowl. 70
2. A liquid-fuel burner comprising a single unitary structure having a fire-bowl with a burner-nozzle therein, a fuel-reservoir extending laterally beneath the bottom wall of the bowl, a steam-generating chamber arranged beneath the bowl, and an air-manifold surmounting the bowl and having its mouth directed downwardly thereinto to distribute the draft around the burner-nozzle. 75
3. A liquid-fuel burner comprising in a unitary structure, a fire-bowl having a burner-nozzle at its center, a fuel-reservoir arranged beneath the bowl in communication with the nozzle, air-ducts leading upwardly at the sides of the bowl, an air-manifold connected with said ducts and provided with a downwardly directed opening arranged above the burner-nozzle, and a steam-generating chamber arranged beneath the bowl and communicating with the air-ducts to provide for the passage of steam thereinto to humidify the air passing to the flame. 80
4. A liquid-fuel burner comprising in a unitary structure, a hemispherical fire-bowl having a burner-orifice, a fuel reservoir extending laterally beneath the bottom wall of the fire-bowl and communicating therewith through the burner-orifice, an annular steam-chamber surrounding the fuel-reservoir, and means for supplying the vapor from the steam-generating chamber to the flame in the fire-bowl. 85
5. In a device of the type specified, the combination in a unitary structure, of a concaved hemispherical fire-bowl, a burner-nozzle at the center of said fire-bowl provided with an inner tapering throat, a fuel-reservoir extending laterally beneath the throat of the nozzle, and an annular steam-chamber surrounding the fuel-reservoir and provided with means for the egress of the steam to apply it to the air supplied to the flame in the bowl. 90
6. In a device of the type specified, a unitary structure comprising a concaved fire-bowl, a fuel-reservoir extending laterally beneath the walls of the fire-bowl, a burner-nozzle opening from the reservoir into the bowl, a steam-generating chamber arranged beneath the bowl, and means communicating with the steam-chamber to direct the vapor to the atmosphere surrounding the burner. 100
7. In a device of the type specified, the combination in a unitary structure, of a fire-bowl having vertical air-ducts at its side, a burner-nozzle within the fire-bowl, a fuel-reservoir beneath the nozzle, a steam-generating chamber surrounding the fuel-reservoir, and an air-manifold resting across the top of the bowl in communication with the air-ducts and having a central downwardly-directed opening surrounding the burner-nozzle. 105
8. A liquid-fuel burner comprising in a unitary structure, a fire-bowl having a concaved hemispherical wall provided with a burner-orifice and an outer cylindrical boundary wall extending therebelow, a bottom wall spaced below the concaved wall, and a vertical wall dividing the space beneath the bowl into a central fuel-reservoir with an annular steam-generating chamber surrounding said reservoir. 110
9. A liquid-fuel burner comprising in a unitary structure, a concaved fire-bowl having a depending outer boundary wall, a bottom wall extending across the space beneath the bowl and joined to the boundary wall, a vertical wall dividing the space below the bowl into a fuel-reservoir having a burner orifice opening into the bowl and an annular steam-generating chamber surrounding the reservoir within the boundary wall, and vertical air-ducts at the rim of the bowl leading upwardly from beneath the bowl. 115
10. A liquid-fuel burner comprising a fire-bowl, a burner-nozzle in the bowl, a draft-flue open to the atmosphere at a point beneath the bowl and arranged to direct the draft of air toward the burner-nozzle, a steam-chamber arranged to be heated by the flame from the burner-nozzle, and a pipe leading downwardly from the steam-chamber and opening to the atmosphere at a point adjacent the intake opening of the draft-flue. 120
11. In a combination with a furnace having a combustion chamber and an ash-pit therebelow, a liquid-fuel burner arranged above the ash-pit and comprising a fire-bowl, a burner-nozzle in the bowl, a draft-flue having an intake opening in the ash-pit and extending to a point above the fire-bowl to direct the draft toward the burner-nozzle, a steam-chamber arranged to be heated by the flame from the burner-nozzle, and a pipe leading from the steam-chamber down into the ash-pit and communicating with the atmosphere in the space surrounding the intake of the air-flue. 125
12. A burner comprising means for burning a gas, a water chamber beneath said means, an air manifold to supply air to said means, and a steam outlet from said chamber into said manifold.

In testimony whereof I affix my signature.

RAYMOND L. FOSTER.
